CLAIM

The ornamental design for a puzzle drawing set, substantially as shown and described.

DESCRIPTION

FIG. 1 is a top plan view of a drawing showing my new design, the side opposite being substantially flat, plain and unornamented;

FIG. 2 is a side elevational view thereof, the side opposite being substantially a mirror image;

FIG. 3 is a left end elevational view thereof; and,

FIG. 4 is a right end elevational view thereof.

FIG. 1

FIG. 2

FIG. 3

FIG. 4
